UNITED STATES PATENT OFFICE.

PETER A. FRIMAND, OF CHICAGO, ILLINOIS, ASSIGNOR OF ONE-THIRD TO
BENJAMIN E. PAGE, OF CHICAGO, ILLINOIS.

DISPENSING DEVICE.

No. 835,606.

Specification of Letters Patent.

Patented Nov. 13, 1906.

Application filed July 10, 1905. Serial No. 268,964.

To all whom it may concern:

Be it known that I, PETER A. FRIMAND, a citizen of the United States, residing at Chicago, in the county of Cook and State of Illinois, have invented a certain new and useful Improvement in Dispensing Devices, of which the following is a full, clear, concise, and exact description, reference being had to the accompanying drawings, forming a part

10 of this specification.

My invention relates to expulsion apparatus from which semifluid substances may be expelled in any desired quantity at any time.

My improved apparatus is adaptable for 15 expelling substances such as jelly, paste, polish, soap, toilet cream, or other semifluid substances which are used in small quantities at a time, and just enough of the substance is delivered upon manipulation of the apparatus to provide for immediate use, the remainder being retained within the receptacle and kept in a sanitary and protected condition.

I am aware that there are devices of this nature on the market; but in these devices the 20 substance is placed directly in the receptacle from which it is to be expelled, and in most cases the receptacle and the substance are sold together, thus making the article very expensive. By means of my invention, however,

25 the substance may be sold in inexpensive holders or cartridges, and one receptacle or expulsion device will serve for expelling the substance from any number of such individual holders. Thus a user of the substances may provide himself with an expulsion device and can buy the uniformly-sized holders containing the various substances and insert them in the expulsion device.

These holders or cartridges may readily be 30 manufactured from paper and may be hermetically sealed to keep the substance in a thoroughly-sanitary condition, and the construction being so simple the cost thereof is very little, which is not true of other expelling 35 devices in which the substance is directly contained.

The exact construction and arrangement 40 of the holder and expelling device can be best understood by reference to the accompanying drawings, in which—

Figure 1 is an elevation view of one form 45 of expulsion device. Fig. 2 is a cross-section taken on a diametrical plane. Fig. 3 is an elevation view of another form of expulsion

device. Fig. 4 is a top view of the receptacle. Fig. 5 shows one form of package. Fig. 6 shows another form of package. Fig. 7 is a bottom view of the packages shown in Figs. 5 and 6. Fig. 8 shows a third form of package which might be used. Fig. 9 shows my invention applied to a shaving-brush, and Fig. 10 shows my invention applied to a paste-brush.

The expelling device 1 is a cup-shaped receptacle, and through its top there is a small outlet 2. The open end of the receptacle is surrounded by a hooked flange 3, over the edge of which engage the spring-clamps 4, extending from the cover-plate 5 and perpendicular thereto is the screw-threaded stem 6, which when the cover is in position extends throughout the full length of the receptacle. A plate or disk 7 has screw-threaded engagement at its axis with the stem 6, and upon turning of the cap and stem the plate 7 will move upwardly or downwardly within the receptacle.

The holder shown in Fig. 5 consists of the body part 8, the cap 9, and the base 10. The body part 8 is primarily a cylindrical tube, and after the base or washer 10 is inserted in one end thereof the ends 11 are curled inwardly to form the retaining-shoulder 12, against which the base 10 may rest. The receptacle thus formed is filled with the desired substance, whereupon the cap 9 is applied and the package sealed to be air-tight.

The holder shown in Fig. 6 is a somewhat modified construction, consisting of the body part 13, with which the cap 14 is integral, the base 10 being applied in the same manner as in Fig. 5. The holder shown in Fig. 8 consists of the body part 15, the upper cap 9, the washer 16, and the lower cap 17, the body part 15 being a cylindrical tube to which the caps 9 and 17 are applied after filling, the washer 16 lying at one end of the package, as shown.

These holders may also be rendered moisture-proof by being saturated with oil or wax and the seams thereof at the caps also filled with wax or oil after filling of the holder. They might also be wrapped in moisture-proof paper.

The washers 10 in Figs. 5 and 6 are provided with the offset central portion 18, which may be shaved off with a penknife before insertion in the receptacle to leave the

opening 19, this opening 19 being already in the washer 16 in Fig. 8. The top wall of the holder shown in Fig. 6 also has an offset 20, which may be cut away before use of the package to leave the opening 21, through which the substance may flow.

When the holder shown in Fig. 5 is used, the cap 9 is removed and the offset 18 cut away to expose the opening 19, and the cap-plate 5, with the stem 6 and washer 7, being removed from the receptacle 1 the holder is inserted top end first to assume the position shown in Fig. 2. The washer or disk 7 having been brought close to the cap 5, the stem 6 is inserted in the opening 19 and forced upwardly through the center of the substance until the clamps 4 engage over the flange 3. The friction between the disk 7 and the base 10 is sufficient to prevent relative motion between these parts, and thus upon relative motion between the receptacle 1 and the cap 5 in the proper direction the plate 7 will move away from the cap 5 and force the washer 10 against the substance within the holder, and the upper part of the substance escapes through the opening 2, and any desired amount of substance can be obtained, depending upon the amount of relative movement between the receptacle and cap 5.

When the holder shown in Fig. 6 is employed, both the offsets 18 and 20 are removed to expose the openings 19 and 21, and the holder is inserted in the same manner, the substance being discharged through the opening 21 and receptacle-opening 2 upon relative movement between the receptacle and the cap 5. When the holder shown in Fig. 8 is used, the two caps are removed therefrom and a similar procedure as with the other packages is carried out.

The disk 7 is preferably of metal in order to be more lasting against the wear at the threads and may have the extension 22 for engaging in the openings 19 of the package washers or pistons. The receptacle, however, is preferably made of glass, porcelain, or other similar substance, which is proof against the tarnishing or corrosive effects of substances like soap. The sides of the cap member 5 may be knurled, as shown, and the surface of the receptacle at the end thereof may be provided with extensions 23 or similar means whereby a good hold may be obtained thereon to prevent slippage should the hands of the user be soapy or greasy, for instance. Either the receptacle or the cap member also may be secured to a support, a very convenient way being to secure the cap to a support, and when it is desired to use some of the substance the receptacle is turned until the desired amount has issued. In order not to derange the parts, the relative motion between the receptacle and caps should be in one direction, and to prevent rotation in a wrong direction the outer edge

of the flange 3 is provided with ratchet indentations 24 and teeth 25 for engagement by the clamps 4, which are springy inwardly. Relative motion may now be produced between the receptacle and cap in one direction; but the teeth 25 will prevent such rotation in an opposite direction, and thus proper actuation of the expulsion parts is assured, and practically every particle of the substance will be expelled when the disk 7 reaches the end of the threaded stem 6. About the opening 2 also there may be provided an outlet or spout 26, threaded to receive a knurled cap 27, and thus when the device is not in use it will be practically hermetically sealed.

Fig. 9 shows my invention applied to a brush, the construction of the expulsion apparatus being slightly modified to form a suitable handle 28. The brush-supporting ring 29 is adapted for threaded engagement with the outlet 26, and the substance, which may be shaving-soap or polish, for instance, passes through the outlet and into the interior of the brush, to be there used in the ordinary manner.

In Fig. 10 the construction of the device is such as to form an elongated tubular handle 30, and the holder may be filled with sticking paste or paint or other substance which could be used with the brush 31, mounted on the brush-ring 32, having threaded engagement with the outlet 26.

My device may also assume various other shapes and still retain all the features of the invention.

By means of my invention substances can be packed in uniform hermetically-sealed holders or cartridges which may be very inexpensive, and after the holder is inserted in the expulsion-receptacle the substance will still be protected against air and dirt and will at all times be perfectly sanitary. There will also be no waste of the substance; as just sufficient turning motion can be given to expel the necessary amount, and practically every particle of the substance will be expelled from the receptacle. The expulsion device can also be used without the use of a separate holder for the substance; but the substance could be inserted directly into the receptacle, in which case, however, the perimeter of the disk 7 would touch the interior surface of the receptacle, and upon relative motion between the receptacle and the cap the substance would be forced through the opening 2. A washer such as 10 could also be secured to the disk 7 to cause better engagement with the interior surface of the receptacle.

I do not wish to be limited to the modifications herein shown nor to the exact construction and arrangement of the parts of the device, as changes may readily be made without departing from the spirit of the invention.

I claim as new, however, and desire to secure by Letters Patent—

1. A substance-holder for insertion in an expulsion-receptacle, said holder being in the form of a cylindrical shell, an offset portion from one end wall thereof adapted to be removed to leave an outlet-opening, the other end wall being slideable within the cylindrical shell to be engaged by the driving mechanism of the expulsion-receptacle to force the substance through the outlet-opening of the holder and through an outlet of the expulsion-receptacle.
2. A substance-holder for use in expulsion-receptacles, said holder comprising a cylindrical shell and end walls, an offset portion in one end wall adapted to be cut away to leave an outlet-opening, the other end wall being slideable within the shell to force the substance through the outlet-opening.
3. A substance-holder for insertion in expulsion devices, said holder comprising a cylindrical shell and end walls, an offset portion on one end wall adapted to be cut away to leave an outlet-opening, the other end wall being slideable within the shell to force the substance through the outlet-opening, the edge of the shell being turned inwardly to hold said end wall against escape from the shell.
4. A substance-holder for insertion in expulsion devices, said holder comprising a shell having end walls, one end wall having an offset portion adapted to be cut away to leave an outlet-opening, the other end wall having an offset portion adapted to be cut away to leave an entrance-opening for driv-
- ing mechanism of the receptacle in which the holder is to be inserted, said other end wall being slideable within the shell, the edges of the shell being turned inwardly after filling thereof and insertion of the sliding end whereby said end is held within the shell.
5. A cylindrical holder containing a soft substance and adapted for insertion in an expulsion device having a discharge-outlet, an upper end part for the holder adapted to be removed to offer an outlet-opening to register with the outlet-opening of the expulsion device, and a base for said holder slideable therein and provided with normally closed inlet means for receiving a member of the driving mechanism of the expulsion device when the holder is inserted therein.
6. A substance-holder adapted for insertion in an expulsion-receptacle, said holder having normally closed outlet means at one end for registering with the outlet-opening of the receptacle when the holder is inserted therein, an inclosing wall opposite said outlet means slideable within the holder toward said outlet means, an opening in said movable wall for allowing passage through the holder of a driving member of the expulsion device when the holder is inserted therein, and means for normally closing said inlet-opening.

In witness whereof I hereunto subscribe my name this 6th day of July, A. D. 1905.

PETER A. FRIMAND.
